UNITED STATES PATENT OFFICE.

FRANK J. MACDONALD, OF ELLET, OHIO; ASSIGNOR TO THE B. F. GOODRICH COMPANY, OF NEW YORK, N. Y., A CORPORATION OF NEW YORK.

MANIPULATING DEVICE FOR SHEET MATERIAL.

Application filed February 25, 1925. Serial No. 11,525.

This invention relates to devices for manipulating sheet material, as in lasting rubberized-fabric shoe uppers or linings, and the present application is in part a continuation 5 of my application Serial No. 703,905, filed April 3, 1924, as a continuation in part of my application Serial No. 661,191, filed September 6, 1923, and is in part a continuation of my application Serial No. 704,502, filed 10 April 5, 1924.

My chief object is to provide improved means for determinately positioning the margin of a piece of sheet material, especially flexible material such as rubber-shoe fabric, 15 and for firmly anchoring the margin as so positioned. A further object is to provide means of this character adapted to operate upon rubberized fabric, before vulcanization, without becoming clogged with the tacky, 20 unvulcanized rubber. A further object is to provide means of the character described adapted to hold a piece of the material, such as a rubberized shoe lining or a shoe upper, for the reception of a form member such 25 as a last, and to swing the margin of the material against the form member to apply it adhesively thereto after the form member and the material have been brought into contact up to the margin that is held by the 30 said means. Other and more detailed or particular objects will become manifest in the following description.

In accomplishing these objects I provide, in the case of the shoe-lasting mechanism, 35 herein described, for example, a pair of nipper jaws having a projective and retractive movement past an abutment member, the jaws being adapted to stand open in their projected position to receive a margin of the shoe upper between them, to be lightly closed and retracted to draw the edge of the upper against the abutment member and thereby determinately position it, the jaws then sliding on the embraced upper's 40 margin throughout the rest of their retractive movement. I also provide means for more firmly anchoring the margin of the upper in the position to which it is thus drawn, to hold it for the reception of a last, and the nipper jaws, gripping the upper, are adapted 45 to be projected under the last, after the latter has been forced into the upper, to swing the upper's margin onto the sole face of the last or onto an insole previously assembled 50 with the last.

While the manipulating devices described herein are especially adapted for use in lasting machines, my invention is not wholly limited to such machines.

Of the accompanying drawings:

Fig. 1 is a perspective view of a nipper unit embodying a preferred form of my invention as employed in a lasting machine, and adjacent parts of the machine.

Fig. 2 is a side elevation of the same 65 together with mounting and cooperating members therefor and the work in its relation thereto, at an early stage of operation.

Fig. 3 is a side elevation of the same at a 70 later stage of operation.

Fig. 4 is a side elevation of the same at a 75 still later stage.

Fig. 5 is a perspective view of a modified form of nipper unit adapted for work upon heavier materials.

Fig. 6 is a side elevation of the same 80 together with mounting and cooperating members therefor and the work in its relation thereto, at an early stage of operation.

Figs. 7 to 10 are side elevations of the same 85 at successive stages of operation.

Referring first to the embodiment shown in Figs. 1 to 4, the nipper unit comprises a generally L-shaped carrier or finger structure 10 including a pair (Fig. 1) of upstanding, parallel side plates 11 held apart by and secured to, by rivets or welding, a spacing block 12 at their upper ends, a spacing block 13 near their middle, and the base of an actuating lever 14 at their lower ends, 90 said lever constituting the foot of the L, projecting horizontally away from the work.

The finger structure 10 is pivoted on a horizontal axis 15 in the forked upper end of a post 16 rising from and adjustably held in an aperture of an annular, stationary frame 17 by a set-screw 18 (Figs. 2 to 4). The annular frame 17 is adapted to permit the vertical passage therethrough of a last support 19, a last 20 resting in upright 100 position thereon and an insole 21 interposed between the last support and the last, suitable means (not shown) being provided for vertically moving the last support in a vertical path to carry the last into association with a conoidal upper or shoe-lining 22 held for the last's reception by a multiplicity of the nipper units, mounted upon the frame 17 similarly to the one here described, 105 and surrounding the lasting position.

For tilting the finger structure away from the lasting position to hold the upper spread to receive the last, a downwardly extending chain 23 connects the lever 14 with a post 24^a adjustably secured, by a set screw 24^b, in a vertically reciprocable, annular, actuating frame 24, and for tilting the finger structure in the opposite direction and causing it to bear yieldingly against the last 10 the lever 14 is connected by an upwardly extending pull spring 25 with one arm of the head of a T-shaped post 26 tiltably set in a depression 27 formed in the upper face of the frame 24, the lever 14 of the adjacent 15 finger structure preferably being similarly connected with the other arm of the said head, so that the post is stabilized.

Pivoted at 28 on the upstanding arm of the finger structure 10 are a pair of parallel, 20 curved side plates 29^a, 29^b held spaced apart by and secured to the base of an arcuate cam lever arm 30 which projects outwardly therefrom, said side plates constituting a substantially C-shaped jaw-actuating lever 29 25 for a pair of nipper jaws 31, 32 pivoted between said plates at their upper ends, at 29^b, and slidably extending between the upper end portions of the side plates 11 of the finger structure 10. The upper jaw 31 is 30 preferably formed with a pointed work-engaging end, so as securely to engage the upper's margin in swinging it onto the insole.

The lower jaw, 32, is adapted to run upon 35 a cam roller 33 mounted between the side plates 11 and its lower roller-contacting face is curved downwardly near the front end of the jaw to provide a cam face, 34, adapted, by cam-action against the roller as the jaws 40 are retracted past the side plates 11, to raise the front ends of the jaws and cause the latter to carry the margin of the upper 22, gripped by the jaws, firmly against oblique points, such as the one shown at 35, formed 45 on the front edges of the side plates 11 respectively by the cutting therein of respective notches, such as the one shown at 36. The lower jaw 32, thus raised by the cam roller 33, is adapted to anchor the upper 22 firmly upon the points 35, which in effect 50 constitute a third nipper jaw, to hold the upper while the last 20 is forced thereinto.

For holding the jaws 31, 32 lightly closed except when they are approximately at the 55 limit of their forward projective movement past the finger 10, a pair of side plates 37^a, 37^b, constituting a double-plate dog 37, are pivoted on the finger at 38 and a cam roller 39 is journaled between their free ends and is 60 adapted to run upon the upper face of the upper jaw 31. A pull spring 40 connects an intermediate part of the dog 37 with the lower part of the jaw-actuating lever 29, the spring's point of attachment to the dog 65 37 being closer to the latter's pivot 38 than

the spring's point of attachment to the lever 29 is to the latter's pivot 28, so that, because of its different moment arms on the two, the spring is adapted to urge the jaw-actuating lever 29 about its pivot 28, in the jaw-projecting direction, as well as to cause the cam roller 39 to bear upon the upper face of the upper jaw 31. 70

For limiting the projective movement of the jaws the lower jaw 32 is extended rearward, past its pivot 29^b, and in the rear end of said extension, 32^b, is mounted a cross-pin 41, the projecting end portions of which are adapted to abut the side plates 29^a of the lever 29. 75

For quickly opening the jaws 31, 32, by lifting the upper jaw 31, at the end of their projective movement, the said upper jaw is formed, adjacent its pivot 29^b, with an upwardly projecting lug 42 having a curved abutment face 43 in extension of the roller-contacting upper face of the jaw, said abutment face being adapted to be engaged by the roller 39 and thereby, by reason of its angular relation to the pivot 29^b, to cause the upper jaw 31 to swing to a determinate open position, in which it is held, against movement in either direction, by the roller 39 fitting in the bay at the junction of the abutment face 43 with the straight portion 95 of the jaw's upper face. 90

For effecting the retractive movement of the jaws 31, 32 past the finger 10 and concurrently closing the jaws, a vertically reciprocable annular frame 44 surrounding the set of nipper units has adjustably secured therein adjacent each nipper unit, by a set screw 45, a downwardly projecting bar 46 slotted at its end to straddle the arcuate lever arm 30 of the nipper unit and provided with a roller 47 journaled within its slot and adapted to bear upon said arm to turn the latter, together with the lever 29 to which said arm is secured, about the pivot 28, in the jaw-retracting direction, when the said frame 44 is lowered. The lever 29 and its arcuate arm 30 are so formed that at the limit of such jaw-retracting movement the roller-engaging upper face of the arm 30 is concentric with the pivot 15 of the finger 10, so that the latter may be tilted toward the last, by the pull of the spring 25 as the frame 24 is lifted, as shown in Figs. 2 and 3, without substantial modification of the jaw-retracting force of the roller 47 upon said arm. 110

For assisting the spring 40 in its jaw-projecting action, a supplemental pull spring 48 may be interposed between the jaw-retracting frame 44 and the outer end of the lever arm 30, as shown in Figs. 2 to 4. 120

The upper end portions of the side plates 11 of the finger 10 are preferably turned backward to provide an oblique reach 49 to serve as a guide for directing the margin of the upper approximately to a determinate 130

position on the lower jaw as the upper is received, and to provide a rounded elbow to bear against the work.

The last support 19 is preferably formed with a bevel 19^a about its work-contacting upper face, to serve as a guiding surface disposed at a suitable angle to permit the lower jaw 32 to slide thereon under the force of the springs 40, 48 in the projective, marginally applying movement of the jaws.

In the operation of this embodiment of Figs. 1 to 4, the shoe upper 22 is mounted with its sole margin between the jaws 31, 32 while the latter stand open in their projected position, shown in Fig. 1, the finger-tilting frame 24 being in its lowermost position to hold the several fingers 10 in determinate positions such as to correspond substantially to the circumferential size of the upper, and the jaw-retracting frame 44 being in its uppermost position to permit the springs 40 and 48 to hold the jaws in their projected positions, with the upper jaw 31 held raised by the roller 39.

The frame 44 is then lowered, which retracts the jaws past the finger 10, and at the beginning of this movement the upper jaw 31 is swung downward by the roller 39, the jaws thus being lightly closed upon the upper, drawing its margin into the recess 36 until the upper's edge abuts the wall of said recess, and thereafter sliding on the upper until the cam face 34 of the lower jaw contacts with the roller 33 to force the jaws upward and thereby anchor the upper on the points 35 as shown in Fig. 2. The jaws 31, 32 are of such length as to embrace a wide margin of the upper and thus in effect to stiffen or brace it against the force of the finger against which its edge is drawn, and thus to prevent crumpling of the said margin by such force.

The last support 19 with the insole 21 and last 20 thereon is then raised, while the upper is thus held at numerous points about its margin, to force the last into the upper.

The finger-tilting frame 24 is then raised, which causes the pull springs 25 to tilt the nipper units against the last, as shown in Fig. 3.

The jaw-actuating frame 44 is then raised, which permits the springs 40, 48 to move the jaws to disengage the upper from the points 35 and to project the jaws 31, 32 against the bevel 19^a of the last support and to cause them to slide upward thereon and thus swing the upper's margin onto and stick it to the lower face of the insole 21, as shown in Fig. 4, the last being held down upon the last support 19 by hand. The upper is preferably provided with rubber cement only along a narrow marginal zone, as shown at 50. The jaws, being guided by the bevel 19^a of the last support, are adapted to apply this zone at a determinate

distance from the edge of the insole, and any slack in the marginal portion of the upper is then taken up by recoil of the elastic upper past the sole margin of the last.

The downward manual pressure upon the last is then released, whereupon the further jaw-projecting action of the springs 40, 48 cause the jaws to ride up over the last support and the upper jaw 31 to swing upward to the position of Fig. 1, lifting the last, with the shoe parts thereon, and supporting it so that it may be freely lifted from the machine.

The last support is then lowered and the operation as described is repeated.

In the modification shown in Figs. 5 to 10, which is especially adapted for operating upon relatively heavy material such as that of canvas tennis-shoe uppers, a special pair of heavy gripper jaws are provided for securing the fabric after the latter has been positioned therein by the projective and retractive nipper jaws.

Each gripper unit comprises an L-shaped lever or jaw carrier 51, which is provided at its elbow with a pair of pivot studs such as the one shown at 52, by which it is pivoted in a vertical closed slot 53 formed in the forked upper end of a post 54 adjustably secured in a stationary, annular frame 55 by a set screw 56.

The carrier 51 has an upright jaw-carrying arm 57 and a horizontal actuating arm 58, an intermediate part of the latter being connected with an annular actuating frame 59 by a lost-motion link 60 adapted to permit the carrier to pivot toward the lasting position, and also to permit it to rise vertically to the extent permitted by the slot 53 in the post 54, when said actuating frame is in elevated position.

The carrier is adapted to be so pivoted and raised by the force of a compression spring 61 interposed operatively between the arm 58 and the frame 59, said spring being mounted upon a spring rod 62 pivoted at 63 to the outer end of the carrier-arm 58, extending with a loose fit into an aperture formed in the frame 59, and having such play therein as to permit its necessary angular movement with relation to said frame. The lower end portion of the link 60 is likewise loosely mounted in an aperture in the frame 59 and is provided with a nut 64 below the latter, so that the frame 59 will tilt the carrier away from lasting position, for the reception of the next upper, when said frame is lowered.

The upright arm 57 of each jaw carrier 51 is formed as a pair of parallel plates held in spaced relation by suitable spacing members, and each plate has formed thereon at its upper end a corrugated jaw such as 64, the two jaws being adapted to act as one, and jaws such as the one shown at 65, mating with the jaws 64, are formed

on a lever 66 consisting of a pair of spaced apart plates straddling the vertical carrier arm 57 and pivoted thereto at 67. The lever 66 is formed with an outwardly projecting arm having an arcuate upper face 68 which is concentric with the pivot 52 of the jaw carrier when the jaw 65 is in closed position, so that said jaws may be held closed, by a roller 69 mounted upon an upper annular actuating frame 70 and running upon the arcuate upper face 68 of the lever 66, while the carrier is tilted toward the lasting position from its upper-receiving position. For drawing the margin of a conoidal upper 71 into the jaws 64, 65, and abutting its edge against the latter at their angle, to position the upper for the reception of a last 72, a pair of upper positioning jaws 73, 74, adapted to grip the upper lightly and slide thereon, and of such length as to embrace a wide margin of the upper and thus in effect to stiffen or brace it against the resisting force of the jaws 64, 65 against which it is drawn, are mounted between the side plates of the vertical carrier arm 57 and between the members of the double jaws 64 and of the double jaws 65, and are hinged together at 75, the upper jaw 73 being forked at its hub to straddle the lower jaw 74, and the latter having a rearward extension 76 pivoted at 77 to a crooked lever 78, said lever being pivoted at 79 to the vertical jaw-carrier arm 57. The crooked lever 78 is thus adapted to project and retract the jaws 73, 74, past the corrugated jaws 64, 65, the lower jaw 74 running upon a roller 80 journaled between the plates of the arm 57, on the pivot pin 67 of the gripper jaws.

For urging the jaws 73, 74 toward their projected position, a pull spring 81 connects an intermediate part of the lever 78 with the vertical carrier arm 57, and for retracting them against the force of said spring the lever 78 is formed with an arcuate upper face 82 adapted to be engaged by a roller 83 mounted upon an intermediate annular actuating frame 84, said arcuate face 82 being concentric with the pivot 52 of the jaw carrier 51 when the sliding jaws 73, 74 are in retracted position, so that the roller 83, running upon the face 82 of the lever 78, may hold them so retracted while the jaw carrier tilts from its upper-receiving position toward the lasting position.

For urging the jaw 73 toward closed position except at the end of its projective movement, for there opening it, and for urging the gripper jaw 65 toward open position, a double-plate dog 84 has its plates pivoted at 85 to a downward extension from the rear arm of the lever 66, said dog having a roller 86 journaled between its plates at its forward end, adapted to run upon the upper face of the jaw 73 for holding the latter closed, and to engage a projection 87 upon said jaw at

its hub for swinging the jaw upon, and the plates of said dog being formed mid-way of their length with respective upstanding arms, such arms constituting a lever 88 which is connected with a pull spring 89 with a part of the lever 66 adjacent the latter's hub. Thus the dog 84, by the force of said spring urging it about its pivot 85, is adapted to bear yieldingly upon the jaw 73 as the jaws 73, 74 are projected and retracted, and also to exert upward force upon the lever 66 at its pivot 85 for urging the lever 66 and its corrugated gripper jaw 65 toward open position, the dog 84 also being so disposed that when the jaws 73, 74 reach the limit of their projective movement the roller 86 will engage the projection 87 of the jaw 73 for swinging the jaw 73 open to receive the shoe upper, its open position being shown in Fig. 5.

Secured to the respective plates of the lever 66, near their pivot 67, are upstanding, angled plates, spaced apart to accommodate the jaws 73, 74 and the gripper jaws 64, and constituting a guide finger 90 for directing the margin of an upper into the jaws 73, 74 and guiding it so that it will clear the upper end of the upstanding jaw carrier arm 57, as will be clear upon reference to Fig. 5.

The jaws 73, 74 are adapted to be limited in their projective movement by contact of the hub portion of the jaw 73 with the carrier arm 57, as shown in Fig. 5, and in their opening movement by the roller 86 fitting into the bay formed at the junction of the projection 87 with the main portion of the jaw 73, and the jaw 65 is adapted to be limited in its opening movement by contact of shoulders such as 91, formed on the side plates of the lever 66, with stop lugs 92, formed on the side plates of the carrier arm 57.

The roller 69 which runs upon the lever 66 for closing the jaw 65, is journaled at the end of a spring arm 93, which is adapted to yield to compensate for relatively great thickness of the upper where seams occur, and said arm is welded to a bracket 94 screw bolted to the outer face of the frame 70. A set screw 95 threaded through the frame 70 bears upon the spring arm 93 and is adapted to be adjusted to vary the force with which the jaws 64, 65 grip the margin of the upper.

The roller 83, which runs upon the lever 78 for retracting the upper positioning jaws 73, 74, is journaled at the end of a rigid arm 96 pivoted at 97 to a bracket 98, screw bolted to the outer face of the frame 84. A set screw 99 threaded through the frame 84 bears upon the arm 96 and is adapted to be adjusted to determine the position to which the upper-positioning jaws are retracted. A C-spring 100 so connects the bracket 98 with the arm 96 as to hold the latter against the set screw 99 when the roller 83 is lifted clear

of the lever 78. The roller 69 may also be lifted clear of its lever 66, as shown in Fig. 6, and this arrangement permits the use of mechanism adapted to raise and lower the frame 70 and 84 through an unvarying distance while permitting variation, as described, in the operation of the two sets of jaws.

The lever 78 is preferably provided at the corner thereof most remote from its pivot 79 with a pair of projections 101, 101 adapted to straddle the lever arm 58 of the carrier 51 when the upper-positioning jaws 73, 74 are retracted and the gripper jaws 64, 65 are closed, as shown in Fig. 7, so as to brace the jaw actuating mechanism while the last is forced into an upper held by the jaws. A last carrier 102 is provided for raising the last and an insole 103 interposed between the two.

It will be understood that when the invention is applied to a lasting machine a plurality of the manipulating devices herein described and claimed are mounted upon the annular frame 55 at spaced positions about the lasting position and are adapted to be concurrently actuated by the frames 59, 70 and 84.

In the operations of the machine, the frame 59 being in its lowermost position to hold the carriers at positions corresponding to the size of the upper 71, and the frames 70 and 84 being in their uppermost positions so as to permit the spring 81 to hold the jaws 73, 74 in their projected position and the spring 89 to hold both pairs of jaws open, the upper 71, provided with a coating of cement 104 along the edge of its sole margin, is mounted upon the set of gripper units, the lower or sole margin of the upper being received between the guiding finger 90 and the lower upper-positioning jaw 74.

The frame 84 is then lowered, which causes the upper-positioning jaws 73, 74 to close lightly upon the margin of the upper, under the force of the spring impelled dog 84, and to slide downward and outward thereon, the lower jaw 74 running upon the roller 80, this stage of operation being shown in Fig. 6. The margin of the upper is thus drawn into the angle of the gripper jaws 64, 65, its edge abutting them at their angle, and the upper is thus accurately positioned for the engagement of the gripper jaws therewith, the jaws 73, 74 sliding on the upper after its edge has thus been positioned.

When the upper positioning jaws have thus been retracted to their outermost position, as shown in Fig. 7, the frame 70 is lowered, which causes the gripper jaws 64, 65, to close upon the margin of the upper as shown in Fig. 7, and said gripper jaws engage the upper's margin to a determinate depth to its edge, because of the positioning of the upper as just described.

When the upper is thus firmly gripped by the jaws 64, 65, the last carrier 102, with the insole 103 and last 72 thereon, is raised to force the last upward into the upper 71, as shown in Fig. 7.

The frame 59 is then raised, which causes the compression spring 61 to tilt the jaw carrier 51 inward against the last carrier 102, as shown in Fig. 8, the rollers 69, and 83 running upon the arcuate faces of the levers 67 and 68, to hold all of the jaws closed and to hold the upper positioning jaws in their retracted position with relation to the gripper jaws 64, 65, while the jaw carrier 51 is thus tilted, the rollers 69 and 83 also preventing the jaw carrier 51 from rising in the slot 53 of the post 54, as it is urged to it by the compression spring 61.

Next the frames 70 and 84 are lifted, which permits the jaw carrier to rise in the slot 53, the jaw 65 bearing against the last support 102 in sliding contact therewith, and all jaws being held closed by the rollers 69 and 83 until the jaws 64, 65 thus carry the margin of the upper into contact with the insole 103. As the frames 70 and 84 continue to be raised, the frame 59 is lowered, and the lifting of the rollers 69 and 83, and the releasing of the force of the spring 61, permits the jaws 64, 65 to open and permits the spring 81 to project the jaws 73, 74, while the latter are held closed by the roller 80 and the dog 84, but with a decreasing force as the pivot 75 of said jaws approaches the roller 86 of said dog. By such projective movement the jaws 73, 74 apply to the insole 103, the portion of the upper's margin theretofore engaged by the gripper jaws 64, 65. During the actuation of the jaws 64, 65, the work is preferably held down by hand upon the last support 102 with such pressure as to hold it thereon until all of the gripper units have come to bear upon the insole and with sufficient pressure firmly to anchor the margin of the upper.

The downward pressure upon the work is then released, whereupon the jaws 73, 74, further projected by the spring 81, lift the last from its support by a cam action of the lower jaw 74 against the last support 102. As soon as the front ends of said jaws rise upon the last support in sliding engagement therewith as shown in Fig. 9, they are projected over said support. As the jaws 73, 74 are thus further projected they release their grip upon the upper's margin and the jaw 73 slides upon said margin toward its edge and thus irons it out against the insole. Then as the work is further permitted to rise the jaw 73 slides outward in contact with the lower face of the work and is thus returned to full open position by the roller 86 of the dog 84, engaging the projection 87 on the hub of said jaw.

The continued lowering of the frame 59 then causes the link 60 to tilt the jaw carrier 51 outward and draw it downward in the slot 53, to return it to its upper receiving position. Meanwhile the last support 102 is lowered, while the work is lifted from the machine by hand, and the operation as just described is then repeated.

Further modifications may be resorted to 10 without departing from the scope of my invention and I do not wholly limit my claims to the specific embodiments here shown.

I claim:

1. A sheet-manipulating device comprising a positioning member adapted to be abutted by the edge of the sheet to position the latter, means for drawing the sheet against said member to position it with its edge against the same, and means for determinately so moving the positioned margin with relation to the rest of the sheet as to give the sheet a complex form.
2. A sheet-manipulating device as defined in claim 1 including means, additional to the positioning member and the drawing means, for effecting a secondary gripping and manipulation of the margin of the sheet after it has abutted the positioning member.
3. A sheet-manipulating device comprising a positioning member adapted to be abutted by the edge of the sheet, a sheet-drawing member adapted to embrace a wide margin of the sheet such that the sheet is in effect appreciably stiffened and to bear yieldingly against the sheet, said sheet-drawing member being mounted for determinate movement with relation to the said positioning member to draw the edge of the sheet against the same, and adapted to slide upon the sheet in further movement after the sheet has been stopped by contact of its edge against the said positioning member.
4. A sheet-manipulating device comprising a positioning member adapted to be abutted by the edge of the sheet, a pair of jaws mounted for projective and retractive movement with relation to said positioning member and adapted to be held open while projected, to receive the margin of the sheet between them, means for closing said jaws upon the margin of the sheet and retracting them to draw the edge of the sheet against said member, and means for projecting the said jaws while holding them closed upon the margin of the sheet to move the said margin determinately away from the said positioning member.
5. A sheet-manipulating device comprising a positioning member adapted to be abutted by the edge of the sheet, a pair of jaws mounted for projective and retractive movement with relation to said positioning member and adapted to be held open while projected, to receive the margin of the sheet

between them, means for closing said jaws upon the margin of the sheet and retracting them to draw the edge of the sheet against said member, the jaws being adapted to slide upon the sheet as their retractive movement continues after the sheet has thus been positioned against said member, and means for projecting the said jaws while holding them closed upon the margin of the sheet to move the said margin determinately away 75 from the said positioning member.

6. A device as defined in claim 5 in which the means for closing the jaws comprises respective members bearing against and running upon the outer faces of said jaws and yielding means urging one of said members toward jaw-closing position.

7. A device as defined in claim 5 which includes yieldingly impelled cam means for opening and closing the jaws as an incident 85 of their projective and retractive movement.

8. A sheet-manipulating device comprising a positioning member adapted to be abutted by the edge of the sheet, a pair of jaws mounted for such relative movement as 90 to be projected and retracted past the positioning face of said member, and means adapted relatively to run on said jaws to close the same as they are retracted and to permit them to open as they are projected. 95

9. A device as defined in claim 8 in which the jaw-closing means is adapted to close the jaws lightly in the first part of their retractive movement and more firmly in the latter part of said movement. 100

10. A sheet-manipulating device comprising a positioning member adapted to be abutted by the edge of the sheet to position the latter, a pair of jaws mounted for projective and retractive movement with relation to the positioning face of said member, and means for closing and retracting said jaws to draw a sheet against said positioning member, said positioning member and said jaws being so mounted as to be moved 110 as a unit to manipulate the sheet while its margin is held by said jaws.

11. A sheet-manipulating device comprising a member adapted to be abutted by the edge of the sheet, a pair of jaws adapted to be held open while projected past said member, to receive the margin of the sheet between them, means for closing said jaws upon the margin of the sheet and retracting them to draw the edge of the sheet against 120 said member, the jaws being adapted to slide upon the sheet as their retractive movement continues after the sheet has thus been positioned against said member, and means for more securely anchoring the margin of the 125 sheet when it has been so positioned.

12. A sheet-manipulating device comprising a member adapted to be abutted by the edge of the sheet for positioning the latter, a pair of jaws mounted for projective and 130

retractive movement of translation to receive the sheet and to draw the edge of the same against said member, a jaw-actuating member adapted yieldingly to bear on one of said jaws and to run thereon to urge it toward closed position during the sheet-drawing retractive movement, the said jaw being provided adjacent its hub with a cam face adapted to be engaged by said jaw-actuating member to open said jaw near the end of its projective movement.

13. A sheet-manipulating device comprising a carrier, positioning means on said carrier adapted to be abutted by the edge of the sheet to position the latter, means for drawing the edge of the sheet against said positioning means, means for anchoring the margin of the sheet so positioned, means for actuating said carrier while the said margin is so anchored, and means for projecting the said drawing means in fixed engagement with the margin of the sheet to move the said margin away from the said positioning means.

14. A sheet-manipulating device comprising a pivoted jaw-carrier, a lever pivoted on said carrier, a pair of jaws on said lever adapted to be projected and retracted with relation to said carrier by movement of said lever, means for opening and closing said jaws as an incident of their projective and retractive movement, said lever being formed with an arcuate face which is concentric with the pivot of said carrier when the jaws are in a determinate part of their range of projective and retractive movement, and means adapted to run on the arcuate face of said lever to hold said jaws in determinate relation while permitting said carrier to be turned on its pivot.

15. A sheet-manipulating device comprising a pair of jaws, means for drawing a piece of sheet material thereinto, means for closing the jaws to grip the margin of the sheet, and means for effecting such relative movement between the gripped margin and the rest of the sheet as to give the sheet a complex form.

16. A sheet-manipulating device comprising a jaw-carrier, a pair of gripper jaws mounted on said carrier, a pair of sheet-positioning jaws mounted on said carrier and adapted to draw the margin of the sheet into said gripper jaws, levers mounted on said

carrier for actuating the respective pairs of jaws and formed with cam faces, and separately mounted means adapted to bear upon said cam faces for actuating said jaws and to run thereon to hold them in determinate relation while permitting said carrier to be actuated.

17. A sheet-manipulating device comprising a jaw-carrier, a gripper jaw fixed thereon, a mate for said gripper jaw movably mounted on said carrier, and a pair of sheet-positioning jaws mounted on said carrier for projective and retractive movement with relation to said gripper jaws for drawing the margin of a sheet thereinto.

18. A sheet-manipulating device comprising a jaw-carrier, means thereon adapted to be abutted by the sheet for positioning the latter, a pair of jaws mounted on said carrier for projective and retractive movement to receive the sheet and draw it against said positioning means, means for holding the jaws closed throughout a part of their range of projective and retractive movement and for holding them open at the limit of their projective movement, and means on said carrier for guiding a sheet into said jaws as they are thus held open.

19. A sheet-manipulating device comprising an abutment member for positioning the edge of the sheet, a pair of sheet-positioning jaws, means for projecting and retracting said jaws past the abutment face of said member and for holding them open at the forward part of their projective range of movement, additional means for guiding a sheet into said jaws as they are thus held open, and a single carrier constituting a mounting for all of the defined parts.

20. A sheet-manipulating device comprising an abutment member for positioning the edge of the sheet, a pair of sheet-positioning jaws, means for projecting and retracting said jaws past the abutment face of said member and for holding them open at the forward part of their projective range of movement, and additional means adapted by sliding engagement with the sheet to guide the latter into said jaws as they are thus held open.

In witness whereof I have hereunto set my hand this 23rd day of February, 1925.

FRANK J. MACDONALD.
